GARMENT HANGER CLAMPING MECHANISM

George M. Lane, Greensboro, N. C.

Application January 6, 1950, Serial No. 137,199

2 Claims. (Cl. 223—91)

1

This invention relates to a garment hanger clamping mechanism and has for an object to provide an improved garment hanger clamping mechanism of the type that will provide means for clamping either a skirt or a pair of trousers between a bar and a clamping bar.

A further object of this invention is to provide an improved means for supporting a skirt or pair of trousers by clamping it against a bar which may be the bar of a coat hanger.

Still a further object of this invention is to provide an improved clamping means for releasably clamping a clamping bar against a bar of a garment hanger to secure a skirt or trousers thereby.

Still a further object of this invention is to provide an improved clamp operating mechanism and operating handle which will hold the clamping bar in open position for the ready insertion of the skirt or trousers between the clamping bar and the garment hanger bar and which will secure the clamping bar in clamp position firmly holding the skirt or trousers between the clamping bar and bar.

A further object of this invention is to provide a garment hanger whose operating mechanism is an improvement over that shown in U. S. Patents Nos. 1,955,792, 2,269,413, and 2,467,623.

Still a further object of this invention is to provide a lever-operated clamping mechanism having spring cams which will move the clamping bar and hold it in open position and move it to clamped position to yieldably hold it in clamped position with varying thicknesses of garments secured thereby.

With the foregoing and other objects in view, this invention comprises the combinations, constructions and arrangements of parts hereinafter set forth, claimed and illustrated in the accompanying drawing wherein:

Fig. 1 is a perspective view of the combination garment hanger in open position.

Fig. 2 is a sectional view on line 2—2 of Fig. 1 of the clamping mechanism, and

Fig. 3 is a view of Fig. 2 in closed position.

There is shown at 10 a combination garment hanger consisting of a coat hanger support 11 having the usual central supporting hook 12 and provided with a bar 13 connecting the lower ends 14 of the coat hanger support portion 11.

As shown the bar 13 is thinned out or cut away at 15 at the center thereof so as to provide space for the seam of the trousers or skirt to be secured therebetween by means of a clamp-

ing bar 16 complementarily cut away at 17 and clamped thereagainst by means of the improved clamping mechanism 18 of this invention.

This clamping mechanism consists of a pair of spring wire portions 20 and 21 and an operating lever 22 having a handle portion 23 and a camming pin 24. The clamping wire portion 20 is formed with a pair of spaced apart legs 25 secured in the bar 13 on opposite sides of the thinned out portion 15 while the clamping wire portion 21 similarly has a pair of spaced apart legs 26 secured to the clamping bar 16 at opposite sides of its thinned out portion 17.

The bight 32 of the spring wire 20 is bent once around the wire 21 as at 28 and then extended downwardly and provides a bight pivot 30 extending through an opening 31 in the lever 22.

The bight 32 has the adjacent portions 33 of legs 21 brought closely together after extending through the bent portions 28 of legs 20 to a distance just greater than the thickness of the lever 22 but less than the length of the camming pin 24. These adjacent portions 33 are bent at 34, again at 35, again at 36 and extend again to a bend 37 where the leg portions separate to extend through the bent portions 28 and then down to the clamping bar 16 at 26. With these bends the camming pin 24 may operate within a triangular shaped cam formed by these bent portions of the bight 32. This triangular cam 38 has its connecting base 40 and an opening side 41 adjacent the bight which is bent inwardly slightly as at 42 while the opposite closing side 43 is substantially straight.

In operation the camming pin 24 is moved by the lever 22 and its operating handle 23 to press against either the opening side 41 riding over the bend 42 to abut against the bight 37 of the angle within the fold 35 or, when the handle 23 is moved in the opposite direction, it abuts against the straight closing side 43 and rides down into the bight of the angle formed by the bend 36. As the lever 22 is pivoted by its aperture 31 on the pivot 30 of the bent bight 37 of the legs 20, it will be apparent that movement of the handle 23 in a clockwise direction as viewed on the drawings will cause the camming pin 24 moving down along the closing side 43 of camming triangle 38 to thereby move the legs 26 of spring wire 21 and press the clamping bar 16 yieldably against the bar 13 thus securing any garment such as a skirt or trousers that has been placed therebetween.

To release the garment from between the

clamping bar and bar, the handle 23 is rotated in a counter-clockwise direction from the closed position of Fig. 3 causing the clamping pin 24 to ride up the straight side 43 then cross over and ride down the opening side 41 past the bend 42 to push this side in a clockwise position and thus cause the legs 26 of spring wire 21 to move the clamping bar 16 away from the position adjacent the bar 13 and thus release the garment held therebetween.

It will be noted in Fig. 3 that the base 40 of the camming triangle 38 is not horizontal but instead extends upwardly from the bend 35 to the bend 36 while in the open position as shown in Fig. 2 this same base 40 now extends downwardly from the fold 35 to the fold 36 (considering the position of the spring wire 20 as being vertical at all times. Thus as the lever 22 is pivoted in either direction, the camming pin 24 riding down the inner side of the camming triangle 38 at the end of its operation always meets one or the other ends of the base 40 to limit the movement thereof and thus hold it set in position either opened or closed as the case may be.

Thus considering the spring wire 20 with its bight pivot 30 as being stationary during operation, the lever 22 pivots at its opening 31 about the bight pivot 30 and cams the clamping bar 16 to open position when moved counter-clockwise and to closed clamping position when moved clockwise to clamp a garment between the clamping bar 16 and the bar 13.

While the preferred form and details of this invention have been thus set forth, described and illustrated, it will be understood that this invention is not limited to such exact details and that changes may be made within the scope of what is hereinafter claimed.

What is claimed is:

1. For use in a garment hanger having a bar and a clamping bar; clamping mechanism mounted on said bar and secured to said clamping bar, said clamping mechanism including a camming means to move said clamping bar between open and closed position and to hold it in either open or closed position, said clamping mechanism comprising a generally U-shaped spring wire member having spaced apart legs secured in said bar, the side leg portions adjacent the bight of said U-shaped spring wire member being bent to provide a pair of spaced apart pivot openings and then bent downwardly providing a bight pivot, a lever having a pivot opening through which said bight pivot extends, said lever having an operating handle, a camming pin extending through said lever and spaced from said pivot opening, a second generally U-shaped spring wire member having spaced apart legs secured in said clamping bar, the upper ends of said latter legs being bent and extending through said bight pivot openings of said first spring wire member to points spaced apart a distance greater than the thickness of said camming lever and less than the length of said camming pin on said camming lever, said upper ends being then bent to form a camming triangle enclosing said camming pin, the

base of said camming triangle limiting the pivoting movement of said camming pin in either direction, the sides of said camming triangle being abutted by said camming pin as said lever is pivoted so that the camming pin moving up one triangular side and down the other triangular side pivots the clamping bar in one direction and moving in the opposite direction pivots the clamping bar in an opposite direction thereby camming the clamping bar to either open or closed position and holding it in either open or closed position when in contact with the base of the camming triangle.

2. For use in a garment hanger having a bar and a clamping bar, said bar and said clamping bar each being cut away on their contacting faces; clamping mechanism mounted on said bar and secured to said clamping bar, said clamping mechanism including a camming means to move said clamping bar between open and closed position and to hold it in either open or closed position, said clamping mechanism comprising a generally U-shaped spring wire member having spaced apart legs secured in said bar at opposite ends of said cut away portion, the side leg portions adjacent the bight of said U-shaped spring wire member being bent to provide a pair of spaced apart pivot openings and then bent downwardly providing a bight pivot, a lever having a pivot opening through which said bight pivot extends, said lever having an operating handle, a camming pin extending through said lever and spaced from said pivot opening, a second generally U-shaped spring wire member having spaced apart legs secured in said clamping bar at opposite ends of said cut away portion, the upper ends of said latter legs being bent and extending through said bight pivot openings of said first spring wire member to points spaced apart a distance greater than the thickness of said camming lever and less than the length of said camming pin on said camming lever, said upper ends being then bent to form a camming triangle enclosing said camming pin, the base of said camming triangle limiting the pivoting movement of said camming pin in either direction, the sides of said camming triangle being abutted by said camming pin as said lever is pivoted so that the camming pin moving up one triangular side and down the other triangular side pivots the clamping bar in one direction and moving in the opposite direction pivots the clamping bar in an opposite direction thereby camming the clamping bar to either open or closed position and holding it in either open or closed position when in contact with the base of the camming triangle.
